UNITED STATES PATENT OFFICE

BERNIE SUMMY HAYTER, OF WACO, TEXAS

CHANGEABLE EXHIBITOR

Application filed February 11, 1932. Serial No. 592,401.

This invention relates to changeable exhibitors, especially adapted for use in store windows and counter advertising.

The invention forming the subject of this application will be found to embody simple and novel means by which separate figures appear to alternately occupy the same space so that the illumination thus produced will attract attention to the device and to the articles associated therewith for advertising and sales purposes.

More specifically, the invention contemplates the utilization of a single source of light for the alternate illumination of the two separate figures on which the illumination is based, the arrangement being such that when one figure is illuminated the same is exposed for direct view, while when the other figure is illuminated, the image thereof is projected onto a combined transparent and reflecting panel directly in line of vision so that the image thus projected appears to take the place of the figure previously seen all to the end that a highly entertaining and puzzling arrangement is produced.

The changeable exhibitor constructed in accordance with this invention will be found to have but few moving parts, and to be of highly simplified construction and comparatively cheap to manufacture.

In the accompanying drawings, forming a part of this application and wherein like reference numerals are employed to designate like parts throughout the same,

Figure 1 is a front elevation of the device; Figure 2 is a horizontal sectional view taken on lines 2—2 of Figure 1,

Figure 3 is a vertical longitudinal sectional view taken on lines 3—3 of Figure 2, and

Figure 4 is a vertical longitudinal sectional view taken on the lines 4—4 of Figure 2.

In the drawings, wherein for the purpose of illustration is shown a preferred embodiment of the invention, the numeral 5 generally designates a substantially rectangular upright casing having a pair of partitions 6 and 7, extending at right angles to each other and joined at the inner corners thereof to divide the casing into diagonally opposite figure-receiving compartments 10 and 12, an illumina-

nating compartment 14 and a panel-receiving compartment 16.

As shown in Figures 2 and 3, a source of light 18 preferably in the form of an electric light bulb, is located within the illuminating compartment 14 and is mounted upon a removable support 20 by which the same may be detached for any one of a number of purposes. A flexible electric cord 22 is shown to have connection with the base of the light bulb 18 and is provided with suitable means such as an attaching plug 24 by which the same may be connected to a source of current.

Figure 3 further illustrates that a cylinder 26 is mounted about the light bulb 18 and is supported for rotation by a standard 28, the upper portion of which is pointed for reception in the bearing 32 in the upper end wall of the cylinder.

The lower end of the cylinder 26 is shown to be fully open for the admission of air while the upper end wall of the cylinder is formed with an annular series of struck-up vanes 34 defining openings for the outlet of air so that the air heated through contact with the bulb is allowed to travel upward through the cylinder and contact the vanes 34 to bring about constant rotation in the same direction as the cylinder.

Now, by reference to Figures 2 and 3 it will be seen that for approximately 180 degrees the cylinder 28 is transparent while the remaining 180 degrees of the circumference of the cylinder is opaque. This arrangement in combination with the vertical light passages 40 and 42 in the partitions 6 and 7 brings about the alternate illumination of the compartments 10 and 12.

More specifically, when the transparent portion of the cylinder 26 is presented to the opening 40 the compartment 10 will be illuminated and when the opaque portion of the cylinder is presented to the opening 40, light will be excluded from the compartment 10. By the same token, when the transparent portion of the cylinder 26 is presented to the opening 42 the figure-receiving chamber 12 will be illuminated and when the opaque portion of the cylinder is presented to the open-

ing 42, light from the compartment 14 will be excluded from the compartment 12.

As shown in Figures 2 and 3, a figure 50 is located within the compartment 10 and for the purpose of this specification may be assumed to be in the form of a female figure, although it may be of any other outline.

In carrying out the invention, a figure 52 is shown to be mounted within the compartment 12 and may be in the form of a grotesque figure of a man although it is clear that any other figure found adaptable may be employed.

Now, with reference to the panel-receiving compartment 16, the same is shown to have positioned therein a diagonally extending combined transparent and reflecting panel 60 and this compartment opens for the full height and width thereof at what might be said to be the inner end into the compartment 12 and at what might be said to be one side thereof for the full height and width thereof into the compartment 10. Also, the front or forward side of the compartment 16 is fully open to form a window or sight-opening through which the observer looks to obtain a direct view of the figure 52 or the reflected image of the figure 50.

More particularly, when the transparent portion of the cylinder 26 is presented to the light passage 42, the figure 52 is illuminated so that an observer may look directly through the panel 16 and see the figure 52. On the other hand, when light is excluded from the compartment 12, the compartment 10 is illuminated and the image of the figure is projected onto the panel 60, this being true because the space in back of the panel 60 is darkened and the panel is thus allowed to function as a mirror.

Figure 2 clearly illustrates that mirrors 74 and 76 line the front and outer walls of the compartment 10 to assist in the full illumination of the figure 50 to the end that the projection of the image of the figure onto the panel 60 is aided.

At this point, attention is directed to the fact that rotation of the cylinder 26 at a substantially constant speed will cut off the supply of light to one of the figure-containing compartments at a rate corresponding to the rate at which the supply of light is furnished to the other figure-receiving compartment so that as the figure 52 comes into view the projected image of the figure 50 will fade from view and vice versa, producing a regulated and not too rapid transition conducive to the complete illusion desired.

Of course, the location of the figures 50 and 52 in the compartments thereof is such that when the image of the figure 50 is projected onto the panel 60 it will be directed in the light of vision to the figure 52 so that there appears to be a physical substitution of one figure for the other.

The casing 5 is provided with a display board 80 upon which tooth brushes 82 or other items, may be suitably mounted and the display board is provided with a sight-opening 84 directly in the line of vision to the figure 52 and it is through this window that the observer looks in the use of the device.

The opposite side walls of the casing are shown to be grooved for the reception of the edge portions of the display board 80 and the top or cover of the casing is removable in any suitable manner to provide for the upward removal of the board 80.

With reference to the foregoing description, taken in connection with the accompanying drawings, it will be seen that an optical illusion device constructed in accordance with this invention is highly puzzling and entertaining and that the attention-attracting feature thus aids in the advantageous display of the items 82 of whatever nature the same happen to be.

The improved changeable exhibitor is automatic in its operation, has few parts and thus requires no special or highly skilled attention.

It is to be understood that the form of invention herewith shown and described is to be taken merely as a preferred example of the same and that such minor changes in arrangement and construction of parts may be made as will remain within the spirit of the invention and the scope of what is claimed.

Having thus described the invention what is claimed is:—

1. In a changeable exhibitor, a casing having partitions arranged approximately at right angles to each other and joined at the inner edges thereof to cooperate in the formation of diagonally opposite figure-receiving compartments, an illuminating compartment and a panel-receiving compartment diagonally opposite the illuminating compartment, said partitions being provided with light passages, figures in said figure-receiving compartments, a single source of light in said illuminating compartment and having means associated therewith to direct a flow of light alternately through said passages into said figure-receiving compartments and to alternately cut off the supply of light to said figure receiving compartments, said figure-receiving compartments being opened into said panel-receiving compartment, and a combined reflecting and transparent panel in said panel-receiving compartment and extending diagonally therein.

2. In a changeable exhibitor, a casing having partitions arranged approximately at right angles to each other and joined at the inner edges thereof to cooperate in the formation of diagonally opposite figure-receiving compartments, an illuminating compartment

ment and a panel-receiving compartment diagonally opposite the illuminating compartment, said partitions being provided with light passages, figures in said figure-receiving compartments, a single source of light in said illuminating compartment and having means associated therewith to direct a flow of light alternately through said passages into said figure-receiving compartments

5 and to alternately cut off the supply of light to said figure-receiving compartments, said figure-receiving compartments being opened into said panel-receiving compartment, a combined reflecting and transparent panel 10 in said panel-receiving compartment and extending diagonally therein, and mirrors within one of said figure-receiving compartments.

3. In a changeable exhibitor, a casing having partitions arranged approximately at right angles to each other and joined at the inner edges thereof to cooperate in the formation of diagonally opposite figure-receiving compartments, an illuminating compartment 25 and a panel-receiving compartment diagonally opposite the illuminating compartment, said partitions being provided with light passages, figures in said figure-receiving compartments, a single source of light in said illuminating compartment and having means associated therewith to direct a flow of light alternately through said passages into said figure-receiving compartments and to alternately cut off the supply of light to said figure receiving compartments, said figure-receiving compartments being opened into said panel-receiving compartment, a combined reflecting and transparent panel in said panel-receiving compartment and extending diagonally 30 therein, and mirrors within one of said figure-receiving compartments, said panel-receiving compartment having an open front constituting a sight-opening affording a view of said panel and the figure located in one of 45 said figure-receiving compartments.

4. In a changeable exhibitor, a casing having partitions arranged in intersecting planes and having their inner edges connected thereby defining diagonally opposite figure-receiving compartments of rectangular form, an illuminating compartment and a panel-receiving compartment, a combined transparent and reflecting panel extending diagonally in said panel receiving compartment 50 and attached to the meeting portions of said partitions, said figure-receiving compartments having openings into said panel-receiving compartments and being in planes approximately at right angles to each other, figures in said figure-receiving compartments and a single source of light having means associated therewith to alternately illuminate said figure-receiving compartments and the 55 figures therein and having means to alternate-

ly exclude light from said compartments, and a removable mounting for said single source of light.

In testimony whereof I affix my signature.
